(57) **CLAIM**

The ornamental design for a controller for interfacing with a computer program, as shown and described.

DESCRIPTION

FIG. 1 is a front perspective view of a controller for interfacing with a computer program showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is top plan view thereof;

FIG. 7 is a bottom plan view thereof;

FIG. 8 is another perspective view thereof; and,

FIG. 9 is perspective view thereof, shown in environmental use.

The broken lines illustrate unclaimed portions of the design. The broken lines in FIG. 9 illustrate environment. None of the broken lines form no part of the claimed design.

1 Claim, 6 Drawing Sheets
